SEAMING HEAD

Neils P. Bach, Geneva, N. Y., assignor to American Can Company, New York, N. Y., a corporation of New Jersey

Application September 3, 1935, Serial No. 39,078

9 Claims. (Cl. 113—24)

The present invention relates to seaming heads in double seaming machines such as are used for the interlocking of flanges of non-circular as well as circular metallic container bodies and their end closures and has particular reference to devices for compensating for wear in the seaming roller and cam follower parts so as to cause the former to accurately follow the contour of a container body for effecting the interlocking of the body and end closure parts in a finished seam of uniform thickness throughout.

An object of the invention is the provision of seaming mechanism of compact and simple construction wherein the seaming rollers are carried in controlled paths of travel around the contour of a can and end closure to be seamed and may be adjusted for wear so that they will accurately follow associated can contour following rollers during the seaming operation to effect an interlocking of the can and end closure parts in a finished seam having a uniform thickness throughout and having the same peripheral contour as that of the container.

Another object is the provision in such a mechanism of devices for shifting the seaming rollers and the can contour following rollers as a unit relative to the controlling means and in respect to the can contour without altering the shape of the path of travel of the rollers around the can contour.

Another object is the provision in a mechanism of this character wherein the seaming rollers may be adjustably moved into alignment with the can contour following rollers and the aligned rollers moved as a unit in respect to the contour of a can to be seamed without disassociation from the controlling means and yet permitting movement between the rollers relative to each other.

Numerous other objects and advantages of the invention will be apparent as it is better understood from the following description, which, taken in connection with the accompanying drawings, discloses a preferred embodiment thereof.

Referring to the drawings:

Figure 1 is a fragmentary vertical sectional view of a can closing machine showing in cross-section a seaming head embodying the instant invention;

Fig. 2 is a horizontal sectional view of the seaming head taken substantially along the broken line 2—2 in Fig. 1, parts being broken back;

Fig. 3 is an elevation of a detail of the seaming head as viewed substantially along the line 3—3 in Fig. 2, parts being broken away;

Fig. 4 is an enlarged perspective view of one of the seaming units;

Fig. 5 is an enlarged part sectional view and part elevation taken substantially along the broken line 5—5 in Fig. 2;

Fig. 6 is a horizontal sectional view taken substantially along the broken line 6—6 in Fig. 5, parts being broken back and other parts removed;

Fig. 7 is an enlarged side elevation and vertical sectional view of the seaming head of Fig. 2, the sectional part being taken substantially along the broken line 7—7 in Fig. 2; and

Figs. 8 and 9 are vertical sectional views taken substantially along the lines 8—8 and 9—9 respectively in Fig. 6.

The preferred form of apparatus disclosed in the drawings comprises a support housing or frame 11 (Fig. 1) which may be part of a seaming machine of either the single spindle or the multiple spindle type. When the machine has a single spindle the housing 11 is stationary, whereas if the machine is of the multiple spindle type, this housing may form part of a rotating element or turret.

The housing 11 supports a seaming head comprising stationary and movable parts. The stationary parts of the seaming head proper are carried on a head sleeve 12 which is held at its upper end in a split bearing formed as a semi-circular boss 13 in the housing. The sleeve is tightly clamped in the bearing by a bearing cap 14 which is formed as part of a housing cover having a depending skirt portion 15 which encloses the front and sides of the entire seaming mechanism. The head sleeve is vertically supported in its bearing on a flanged nut 16 which threadedly engages the upper end of the sleeve and which is screwed tightly on top of the boss 13 and cap 14.

The head sleeve 12 extends down through the movable parts of the seaming head and at its lower end is formed with a laterally extending flange 18. A stationary pattern cam 19 having a cam track 21 is held on the bottom face of the head sleeve flange for guiding seaming rollers in a path of travel around a can to be closed.

The cam is held on the flange by a cam sleeve 22 which is centrally disposed inside the head sleeve 12. The lower end of the cam sleeve is threadedly secured in the cam at its center while the upper end of the sleeve is provided with an enlarged head 23 which rests on top of the upper end of the head sleeve 12 for vertically supporting the cam. By turning the head 23 the cam is drawn up into tight fitting engagement.

with the head sleeve flange 18, the cam being properly located on the flange by dowel pins 24 carried by the latter.

A chuck 26 is secured to the bottom of the cam 19 for cooperative action with the seaming rolls in performing the seaming operation and for locating and assisting holding the cam and can end to be seamed. The shape or contour of this chuck is the same as the shape of the can and likewise the shape of the cam track 21 is of the same shape. These contours are rectangular in form for a rectangular can. For a circular can these contours would be circular.

For holding the can there is provided a lift plunger 31 which is mounted on the upper end of a stem 32, having vertical sliding movement in a bearing 33, formed in a web 34, which projects outwardly from the housing 11 and which extends under the seaming head. The stem is raised and lowered in timed relation with the other moving parts of the machine by any suitable and well known means. Such a plunger supports a can 35 on which a cover or end closure 36 has preferably been loosely applied. As the can and cover are raised with the rising plunger, the cover is pressed against the chuck 26 in the usual manner, the can and cover being clamped stationary between the chuck and the plunger throughout the seaming operation.

The moving or rotating parts of the seaming head proper (Fig. 1) are carried on two separate sleeves, a head frame sleeve 38, mounted on the head sleeve 12, and a seaming cam sleeve 39 mounted on the sleeve 38. The sleeve 39 is journaled in a split bearing formed as a semi-circular boss 41 in a web 42 of the housing 11. A bearing cap 43 formed in the skirt 15 holds the sleeve 39 in the bearing and thus provides a support for all the sleeves and for the lower end of the seaming head.

The upper end of the sleeve 39 is formed with a lateral extending flange 45 which rests on top of the split bearing and which carries a gear 46. The lower end of the sleeve extends below the bearing and is keyed to a barrel cam 47 which is continuously rotated by the gear 46 and which engages with the under side of the bearing thus preventing vertical movement of the sleeve. The cam 47 is held in this position against the bearing by a collar 48 which is disposed in a recess 49 formed in the lower end of the cam, and which threadedly engages the lower end of the sleeve 39.

The upper end of the head frame sleeve 38, like the seaming cam sleeve 39, is also provided with a laterally extending flange 52 which rests on top of the gear 46, and which in turn carries a gear 53. This latter gear is provided with a central hub 54 which encircles the head sleeve 12 and which extends up into engagement with the under side of the bearing 13 and cap 14. This construction prevents vertical end play of the head frame sleeve 38 on the head sleeve 12.

The lower end of the head frame sleeve 38 extends below the end of the cam sleeve 39 and terminates in a shouldered end which carries an inverted dish shaped head frame 55. The head frame is continuously rotated by the gear 53 through the sleeve connection and comprises a central hub 56 which is keyed to the end of the sleeve 38 and is held in place by a collar 57, which threadedly engages the extreme end of the sleeve 38. The hub is formed with a horizontal disc shaped plate 58 which merges at its outer periphery with a depending vertical wall 59 which

extends down over and spaced away from the stationary cam 19.

The head frame 55 carries devices in which the seaming rollers are mounted and which move them into and out of engagement with the can and cover parts while they are moved around the can contour guided by the pattern cam for effecting the seaming operation. There are two sets of these devices, identical in construction and simultaneously actuated but disposed diametrically on opposite sides of the can. Hence it is thought necessary to describe only one device in detail.

The device comprises in part a horizontally disposed pattern cam arm 61 (Figs. 1, 2, 4, 5, 6 and 7) which is formed at one end with a vertical pivot sleeve 62, and this sleeve is mounted in a bearing 63, which projects inwardly from the vertical wall 59 of the head frame 55. The sleeve is held in the bearing by a nut 64 (Fig. 5) which rests on the bottom of a recess 65 formed in the top of the bearing and which threadedly engages a shouldered upper end of the sleeve.

The free end of the arm 61 carries a cam roller 67 (Fig. 7) which is rotatably mounted on a bushing 68 with its lower end in engagement with a shoulder formed by an enlarged depending skirt portion 69. It is this roller which is moved in the stationary pattern cam groove by the rotating head frame for guiding the seaming roller around the can contour. The roller is held on the bushing by a spring ring 70 which engages the top end of the roller and which is disposed in a groove 72 formed in the upper end of the bushing. The bushing in turn is adjustably mounted on screw threads 73 formed on a stud 74 which is riveted into the end of the pattern cam arm 61.

The cam roller 67 engages within the pattern cam track 21 and is provided with upper and lower converging tapered surfaces 76, 77. These surfaces engage with correspondingly tapered surfaces 78, 79 formed in the cam track, the surface 78 being formed in the outer track, while the surface 79 is formed on the inner track, the angles of inclination of all the tapers being equal for a purpose hereinafter explained.

A seaming roller arm 81 is disposed below the pattern cam arm 61 and moves with it. At one end, this arm is formed with a bore 82 the edges of which form a bearing which is mounted on a pivot shoulder 83 of a hollow cap 84. The cap is secured to the bottom face of the arm 61 by screws 85 (Fig. 4) and held in spaced relation thereto by spacer blocks 86 which surround the screws. In this manner the cap supports the seaming roller arm and holds it against the bottom of the cam arm while at the same time providing a pivot for the former which is coaxial with the sleeve 62 of the latter.

The opposite or free end of the seaming roller arm 81 is bifurcated as at 88 (Figs. 4 and 7) and carries a stud 89 on which is mounted a seaming roller 91, the central axis of the stud and roller being in direct alignment with the central axis of the cam roller when the former is directly under the latter.

The seaming roller arm 81 and the cam roller arm 61 are adapted to be moved about their common pivot point as a unit and yet at times they are capable of having movement relative to each other. For this purpose the free ends of the arms are yieldingly tied together by a coiled spring 93 (Figs. 1, 5 and 6). One end of the spring hooks over a pin 94 which is secured in the end of the

seaming roller arm and the other end passes through a swivel block 95 which is mounted in a lug 96 formed as a part of the cam roller arm 61. Movement of the arms relative to each other as when moving the seaming roller into and out of seaming position, is effected by a wedge slide 101 (Figs. 5 and 6) which is horizontally disposed in a channel 102 formed in the bottom of the cam roller arm 61. The wedge slide is held against vertical displacement between the top of the channel and the top of the seaming roller arm 61. The forward end of the wedge slide is formed in a blunt wedge 103 (Fig. 6) the side walls of which merge into a pair of parallel wall sections 104. These latter sections extend into outwardly projecting cam protuberances 105 which form an enlarged part on the sides of the wedge slide. This step form of the wedge slide effects a wedging action when the slide is moved longitudinally. Adjacent one side of the wedge 103 a fixed pin 107 is secured in the top of the seaming roller arm 61 and carries a roller 108 (see Fig. 8 also). The channel 102 in the arm 61 is cut out in a recess 109 to provide clearance for this roller. On the opposite side of the wedge 103 a roller 111 is mounted on a pin 112 which is carried in a lug 113 formed as an integral part of a plate 114. The lug extends through the side wall of the channel 102 in a slot 115 cut in the cam roller arm 61 (see also Fig. 6). The plate is secured to the outside of the arm, one end being held in a tight fitting groove 116 cut in the lug 96 while its other end is held by an adjusting screw 117 which passes through the plate and is threadedly engaged in the arm. This construction permits of adjustment of the roller 111 relative to the cam arm 61 thereby providing a means of shifting the seaming roller arm 61 relative to the cam arm in order to bring the seaming roller into axial alignment with the cam roller. This adjusting or setting of the seaming roller into its proper position is done before actual operation of the machine begins.

Relative movement of the arms 61, 81 in one direction, moves the seaming roller into seaming position. This action is effected by a forward movement (to the right) of the wedge slide 101 which moves the wedge 103 between the rollers 108, 111, causing them to ride up on the step walls 104 and to thereby spread the arms apart or shift them relative to each other against the resistance of the spring 93 and into the position of Fig. 6. For this purpose the wedge slide 101 at its rear end, i. e. opposite to the wedge end 103, is enlarged and is provided with a tapered cam slot 121 (Figs. 5 and 6). The slot is disposed adjacent the central axis of the cam roller arm sleeve 62 and engages with an angularly positioned cam finger 122 having tapered surfaces 123 which correspond and engage with the tapered surfaces of the cam slot. The cam finger is formed on the bottom of a vertical plunger 124 which is slidably disposed inside the sleeve 62.

The plunger is moved up and down in the sleeve 65 to actuate or impart a back and forth movement to the wedge slide 101. For this purpose the plunger extends above the top of the sleeve and carries a collar 125 which is secured in place by a screw 126. The collar is formed with an annular groove 127 which is engaged by a pair of rollers 128 mounted on the inner ends of pins 129 carried in the bifurcated end of a lever 131 (Figs. 2, 3 and 5).

The lever is disposed adjacent the seaming cam 75 47 and at its opposite end it is mounted on a

pivot shaft 132 which is carried in bearings 133 formed on the top of the wall 58 of the rotating head frame 55. Intermediate its ends the lever carries a shouldered stud 135 which is locked in position by a nut 136. One end of the stud extends beyond the lever and carries a cam roller 137 (Fig. 2) which engages within a cam groove 138 of the cam 41. It is the rotation of this cam which actuates the lever 131, the plunger 124 and wedge slide 101 to move the seaming roller 10 into seaming position.

The rotations of the seaming cam 47 and the head frame 55 are effected by what is commonly known as differential gearing, which include the gears 46, 53 hereinbefore briefly referred to. The 15 gear 53 meshes with a gear 141 (Fig. 1) which is mounted on a vertical continuously moving shaft 142, journaled in a bearing 143, formed in the housing 11 and a bearing 144 formed in the web 62. The gear 46 meshes with a gear 145 mounted 20 on the shaft 142 just below the gear 141.

The gears 141, 145 are rotated at a uniform speed but the gear 46, being larger than the gear 53 revolves at a slower speed than the gear 53 and the effect is a retarding movement of the cam 47 25 relative to the revolving head frame 55. In one complete cycle of operation for completing the seaming of a single can, the cam rollers 137 are caused to traverse one half way around the groove 138 in the cam 41.

The shape of the cam groove 138 is such as to move the wedge 103 forward between the rollers 108, 111 causing them to move apart and ride up on the parallel surfaces 104. This action effects the relative movement between the arms 61, 81, 35 40 which brings the seaming roller directly under the cam roller and into seam closing position against the can and its cover flanges to form the seam as shown in Fig. 7. In this position the seaming roller is in axial alignment with the cam roller 40 and remains in this position throughout the entire seaming operation, being guided around the can in this alignment by the cam roller 61 traversing the pattern cam groove 21. In this manner, with a simply constructed pattern cam having the 45 same shape as the can and cover contour and with the seaming roller always in alignment with the cam roller during the seaming operation, the seaming roller is compelled to follow the exact contour of the can and cover and hence a proper 50 seam, especially at the can corners in the case of non-circular cans, is effected.

To compensate for wear in the seaming roller and still maintain the proper axial alignment between the seaming roller and cam roller, an adjustment is provided whereby the arms 61, 81 may be moved as a unit relative to the cam groove 21. This is effected by an adjusting screw 146 (Figs. 4, 6 and 7) which is carried in a bore 147 formed in a boss 148 of the cam arm 61. One end of the 60 screw is provided with a head which is formed with a collar 149 which engages the end of the boss and a reduced slotted part 151 which extends beyond the collar where it is readily accessible for adjustment of the screw by means of a suitable 65 tool. This part of the screw head projects through an opening 152 in a plate 153 which is held in engagement with the collar and the end of the boss by a screw 154 (Fig. 6), thus holding the screw within the bore against longitudinal movement.

The opposite end of the screw 146 is threaded and engages with worm teeth 155 (Figs. 6 and 7) formed in the skirt 69 of the cam roll bushing 68. By rotating the screw the bushing may be turned 75

on the screw threads 73 of the stud 74 and thus raise or lower the cam roller in its track 21. Adjustment of the cam roller in this manner shifts its axis transversely of the groove along its tapered surfaces and simultaneously shifts both arms 61, 81 as a unit moving the seaming roller toward or away from the chuck 26 as the case may be.

After completion of the seaming operation the 10 seaming rollers are withdrawn to enable removal of the closed can. At this time the cam groove 138 moves the plunger 124 upward and causes the cam finger 122 to slide the wedge slide 101 rearward. This action withdraws the wedge 103 from 15 between the rollers 108, 111 so that the rollers ride off the steps 104. This shift in position also moves the protuberances 105 into engagement with a pair of pins 161, 162 and causes the pins to ride upon the protuberances. These pins are disposed one on each side of the wedge slide 101 (see Fig. 6), the pin 161 being engaged in the upper arm 61 (Fig. 9) while the pin 162 is engaged in the lower arm 81. Engagement of the pins by the protuberances 105 spreads or moves the pins 20 apart causing a relative movement between the arms in a direction opposite to that hereinbefore mentioned. This movement of the slide aided by the spring 93 draws the arms 61, 81 toward each other and thus positively withdraws the seaming 25 rollers from seaming position. This action shifts the seaming roller out of alignment with the cam roller which disalignment is maintained until the seaming roller arm is again moved into seaming position.

30 The closed can is now removed from the chuck 26 by the lowering of the lift plunger 31. This removal is assisted by a knockout pad 165 (Figs. 1 and 7) which normally is housed within a recess 166 formed in the bottom of the chuck. The pad is carried on the end of a vertical rod 167 (Fig. 1) 35 which extends up through the center of the chuck 26 and cam 19 into the cam sleeve 22 where it joins with a rod 168 by means of a tongue and groove connection 169. The upper end of the rod 168 extends beyond the sleeve 22 and may be actuated by any suitable means operating in time with the other moving parts of the machine to strip the closed can from the chuck.

The description of one seaming roll and associated cam roll mechanism applies equally as well 40 to the other seaming and cam roll mechanism, there being usually a first and second operation seaming roll needed to produce the well known double seam between can body flange and cover flange.

55 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

60 I claim:

1. In a seaming head for uniting can covers to can bodies, the combination of a seaming roller arm, a seaming roller on said arm for interlocking parts of a said can and cover, a cam roller arm 65 associated with said seaming roller arm, a cam roller on said cam roller arm, a cam track for guiding said cam roller and said seaming roller around a path coincident with the contour of said can and cover, means for adjusting said seaming roller arm relative to said cam roller arm for axi-

ally aligning said rollers, and adjusting means for shifting said cam roller in said cam track for moving said arms laterally as a unit relative to said can and cover for effecting a like relative lateral movement of said seaming roller while maintaining its axial alignment with said cam roller.

2. In a seaming head for uniting can covers to can bodies, the combination of a seaming roller arm, a seaming roller on said arm for interlocking 10 parts of a said can and cover, a cam roller arm associated with said seaming roller arm, a cam roller on said arm, a cam track for guiding said cam roller and said seaming roller relative to rotation between said rollers and said can and cover, means for adjusting said seaming roller arm relative to said cam roller arm for axially aligning said rollers, adjusting means for shifting said cam roller in said cam track for moving said arms laterally as a unit relative to said can and cover 15 for effecting a like relative lateral movement of said seaming roller while maintaining its axial alignment with said cam roller, and means for moving said seaming roller arm independently of said cam roller arm to dis-align said rollers to 20 permit positioning of a can and cover to be seamed and for realigning said rollers to effect the seaming operation.

3. In a seaming head for uniting can covers to can bodies, the combination of a stationary chuck 30 for holding a can and cover to be seamed, a head frame having rotative movement around said chuck, seaming devices including a seaming roller carried on and rotating with said head frame, contour following devices including a tapered cam 35 roller also carried on said rotating head frame and cooperating with a stationary tapered cam track for guiding said seaming devices around the contour of said can and cover, means for adjusting said seaming devices relative to said contour 40 following devices whereby the rollers will be in axial alignment for the seaming operation, automatic means for moving said seaming roller relative to said cam roller and towards and away from said can cover while rotating with said head frame for effecting the seaming operation, and adjusting means for shifting said roller and said seaming roller as a unit relative to said chuck 45 while still maintaining the rollers in their axial alignment.

4. In a seaming head for uniting can covers to can bodies, the combination of a can support for holding a can and cover during a seaming operation, a head frame having rotative movement relative to said support and the can and cover carried thereon, a seaming roller arm carrying a seaming roller for seaming said cover to said can, a cam roller arm associated with said seaming roller arm and carrying a cam roller, a stationary cam track in which said cam roller 60 operates for guiding said seaming roller, around the contour of said can and cover, means for axially aligning said rollers for the seaming operation while still permitting relative movement between them, and adjusting means operable at 65 will for shifting said cam roller in said cam track for moving said arms as a unit relative to said can and cover while maintaining the axial alignment between said rollers.

5. In a seaming head for uniting container 70 covers to container bodies, the combination of a seaming roller for interlocking parts of the container and cover, a cam roller associated with said seaming roller and adapted to move in a controlled path relative to said container and cover, 75

5 a cam track for producing the controlled guiding of said cam roller, and means for adjusting said rollers as a unit relative to said cam track so as to effect a lateral adjustment of said seaming roller.

6. In a seaming head for uniting can covers to can bodies, the combination of a seaming roller for interlocking parts of the can and cover, a cam roller associated with said seaming roller and adapted to move in a controlled path of travel relative to said container and cover, a tapered cam track for guiding said cam roller, and means for adjusting said cam roller in said tapered cam track to laterally adjust said rollers as a unit 10 15 while maintaining axial alignment therebetween.

7. In a seaming head for uniting can covers to can bodies, the combination of a seaming roller for interlocking parts of the can and cover, a cam roller movably associated with said seaming 20 25 roller, a cam track for guiding said rollers as a unit around said can cover, means for adjusting said seaming roller into axial alignment with said cam roller, means for adjusting said aligned rollers as a unit relative to said cam track so as to effect a lateral adjustment of said seaming roller in respect to said can and cover, and means for laterally moving said seaming roller out of and

into alignment with said cam roller for performing the seaming operation.

8. In a seaming head for uniting can covers to can bodies, the combination of a seaming roller arm, a seaming roller on said arm for interlocking parts of a can and cover, a cam roller arm associated with said seaming roller arm, a cam roller on said cam roller arm, a cam track for guiding said cam roller and said seaming roller relative to rotation between said rollers and said can and cover, and means for adjusting said cam roller in said cam track for moving said arms laterally as a unit relative to said can and cover. 10 15

9. In a seaming head for uniting container covers to container bodies, the combination of a seaming roller for interlocking parts of the container and cover, a cam roller associated with said seaming roller, means for moving the cam roller and said seaming roller around said container and cover, a cam track for guiding said cam roller, 20 25 said cam track having inner and outer tapered portions disposed in parallel relation, and means for adjusting said cam roller relative to said cam track in a direction substantially parallel to the longitudinal axis of the container body whereby to effect a lateral adjustment of said seaming roller relative to said container body.

NEILS P. BACH.
